UNITED STATES PATENT OFFICE.

MORRIS W. POOL, OF NEW YORK, N. Y., ASSIGNOR TO THE MONARCH TYPEWRITER COMPANY,
OF SYRACUSE, NEW YORK, A CORPORATION OF NEW YORK.

TYPE-WRITING MACHINE.

No. 909,334.

Specification of Letters Patent.

Patented Jan. 12, 1909.

Application filed April 20, 1906. Serial No. 312,815.

To all whom it may concern:

Be it known that I, MORRIS W. POOL, citizen of the United States, and resident of the borough of Brooklyn, city of New York, in the county of Kings and State of New York, have invented certain new and useful Improvements in Type-Writing Machines, of which the following is a specification.

My invention relates especially to carriage retarding devices for typewriting machines. In machines of this character which employ carriage retarding mechanism, it is usual to connect the retarding mechanism with the traveling element or carriage when the latter is released from its step-by-step feeding means so that at the outset the carriage must overcome the inertia of the movable part of the retarding mechanism. This tends to check the speed of the carriage and so consumes time.

The main object of the present invention is to so connect the carriage with the retarding device that the latter will not be operative until the carriage has been released from its step-by-step feeding means and has been moved freely or caused to jump by the carriage over a distance equal to a plurality of letter spaces. By providing such a connection the inertia of the carriage itself is overcome before it starts to operate the retarder and the time consumed by the carriage in jumping from one position to another in the writing line is materially lessened.

To the above and other ends the invention consists in the features of construction, combinations of devices and arrangements of parts hereinafter fully described and particularly pointed out in the claims.

In the accompanying drawings, Figure 1 is a vertical front to rear sectional view of so much of a typewriting machine as is necessary to illustrate my invention. Fig. 2 is a rear elevation of the machine, parts being omitted and parts being broken away. Fig. 3 is an enlarged fragmentary sectional view of the upper part of the machine taken at the left of the retarding device. Fig. 4 is an enlarged longitudinal sectional view taken through the axis of the retarding device. Fig. 5 is an enlarged transverse sectional view taken through the casing of the retarding device. Fig. 6 is an enlarged perspective view of a part of the retarding device. Fig. 7 is an enlarged sectional view taken on a plane represented by the line $x-x$ in Fig. 4 and looking in the direction of the arrows at said line. Fig. 8 is a view corresponding to Fig. 7 but showing some of the parts in different relations from those in which they appear in said Fig. 7. Fig. 9 is an enlarged perspective view of a modified construction of one of the parts hereinafter termed a toothed rotary member or pinion.

My invention is shown as applied to a typewriting machine generally resembling the Monarch typewriter and in combination with one form of retarding device. It is to be understood, however, that the nature of the invention is such that it may readily be adapted to other styles of writing machines and combined with other forms of retarding devices. The particular retarding device herein illustrated is not claimed *per se* by me as said retarding device is the invention of others.

Referring now to the drawings, the main frame of the machine is shown as comprising a base 1, corner posts 2 and a top plate 3. Printing instrumentalities (not shown) are mounted on the main frame and are coöperative with the front face of a rotary platen 4, said platen being journaled in side bars 5 projecting forwardly from a rear bar 6, said side bars and rear bar constituting a platen frame, carrier or carriage. The top and bottom faces of the rear bar 6 are grooved to coöperate with anti-friction balls 7, said balls also coöperating with top and bottom guide rails 8 and 9, said guide rails being fixed by screws 10 to standards 11 rising from the top plate. Arms 12 are pivoted at 13 in the side bars 5, said arms extending rearwardly from their pivots and carrying at their free ends a carriage rack 14. Rack springs 15 normally maintain said rack in engagement with a carriage pinion 16, said pinion being fixed to the front end of a horizontally disposed shaft 17 journaled in a bracket 18 fixed to the top plate. Operatively connected with said shaft 17 at the rear thereof is an escapement wheel 19, said escapement wheel coöperating with dogs 20 carried at the top of a vibratory dog carrier or rocker 21 pivotally mounted at 22 in a bracket 23 depending from the top plate. The dog carrier is provided with a horizontally disposed and forwardly projecting arm 24 which is connected by a link 25 with a universal bar (not shown) of suitable construction. The universal bar is adapted to be operated each time the printing instru-

2

mentalities are actuated, thereby causing the escapement devices to coöperate in a known manner to permit the carriage and platen to be drawn one letter space at a time 5 leftward across the top plate under the influence of a carriage spring drum 26 pivoted at 27 to the frame of the machine and connected by a band or strap 28 with a pin 29 depending from the rear bar of the carriage.

10 A horizontally disposed and rearwardly projecting carriage stop 30 is secured by screws 31 at the back and about midway of the length of the rear bar of the carriage. Said carriage stop is coöperative with one or 15 more column stops 32 adjustably mounted on a toothed stop bar 33 journaled in lugs 34 projecting rearwardly from the standards 11. A forwardly projecting arm 35 is secured to the right end of the column stop bar 33 by a 20 screw 36. Pivotaly connected with the forward end of said arm at 37 is a vertically disposed link 38, said link extending through suitable openings in the top plate 3 and base 1 and being pivotally connected at its lower 25 end as indicated at 39 with the rear end of an auxiliary lever 40 pivoted to a shouldered screw 41 projecting laterally inward from the right hand side of the base. The auxiliary lever 40 is provided with an upwardly 30 extending portion 42 formed with a slot 43 which receives a pin 44 extending laterally from a tabulating key lever 45 pivoted at 46 to a lug 47 depending from the base. The tabulating key lever is provided at its rear 35 end with a restoring spring 48 and is curved upwardly at its forward end, terminating in a key cap or button 49. Suitably secured to the link 38 beneath the top plate is an arm or lug 50 which is adapted to actuate 40 the carriage releasing and retarding devices in a manner presently to be described. A coiled spring 51 surrounds the link 38 and is confined between the arm 50 and the top of the base 1, said spring tending to maintain 45 the column stops 31 normally out of the path of the carriage stop 30 as indicated in Fig. 1.

It will be understood that when the tabulating key 49 is depressed the column stop bar is turned on its pivotal axis to bring the 50 column stops 32 thereon into the path of the carriage stop 30 as shown in Fig. 3. Thereafter the carriage may be released or freed from its step-by-step feeding mechanism in any suitable manner, as, for example, in the 55 way presently to be described. A lever 52 is pivoted at 53 to a lug 54 depending from the top plate. The right arm of said lever is provided with a stop 55 which is normally maintained in contact with the under side of the 60 top plate 3 by a restoring spring 56 coiled around the pivot of the lever. When in normal position the right arm of the lever 52 lies below and in the path of the arm or lug 50 on the link 38 as shown in Figs. 1 and 2. The 65 inner or left hand arm of the lever 52 is con-

nected in the usual Monarch tabulating mechanism with a rack lifter of known construction, but in the present instance said rack lifter is preferably dispensed with and a link 57 is pivoted to the lever 52 at 58, said link extending upwardly and being bifurcated at its upper end, the arms 59 of the bifurcation coöperating with the retarding device next to be described to move the latter to operative position and to lift the carriage rack 15 to release or free the carriage from its step-by-step feeding mechanism.

The retarding device proper is pivotally supported on a U-shaped bracket 60, which bracket is secured to the right of the bracket 18 of the escapement mechanism by a headed screw 61. The side arms of the bracket 60 extend upward and are formed with bearing openings to receive shouldered screws 62 (Fig. 4), said screws being received in threaded openings in a bearing piece 63 and thereby pivotally connecting said bearing piece with the bracket 60. The bearing piece is bored out to receive a shaft 64, said shaft at its rear having secured to it a plurality of arms or 90 blades 65 (Figs. 4 and 5). The arms 65 are preferably housed in a cylindrical box or casing or stationary retarder element 66 which is suitably secured in a fixed relation with the bearing piece 63. The rear end of said casing is preferably closed by a screw cover 67 and said casing contains a quantity of material 68 which may be either liquid or solid as preferred. Shot or small balls are shown. The bearing piece 63 is provided near its forward end with laterally extending pins 69, which, as best shown in Figs. 3 and 4, enter openings in the arms 59 of the link 57, thereby connecting said link with the tabulating device and enabling the latter to be swung up and down on its pivots 62 from the position shown in Fig. 1 to that shown in Fig. 3, when the tabulating key 49 is operated. The retarding mechanism as thus far described, is not my invention and I do not 110 claim it, save in combination with other features now to be described.

As best shown in Fig. 4 the forward portion of the shaft 64 projects beyond the end of its bearing piece 63. Mounted on the shaft 64 115 abutting against the end of the bearing piece 63, is a cylindrical box-like member or device designated as a whole by the reference numeral 70. Projecting inwardly from the rim 71 of the member 70 is a stop or lug 72 120 and at one side of the stop 72 the rim is formed with a slot or cut-away 73. The member 70 is formed with a central rearwardly projecting boss or hub 74 which is formed with a perforation 75 through which 125 the shaft 64 passes. The boss is provided with a threaded opening which receives a securing screw 76, the inner end of said screw abutting against the shaft 64 and maintaining the member 70 in a fixed relation with 130

said shaft. The member 70 receives the hub 77 of a toothed rotary member or pinion 78, said pinion being provided with radial teeth 79 adapted to coöperate with the teeth of the 5 carriage rack 15. The pinion 78 is loosely mounted on the shaft 64 and is confined between the member 70 and the head of a retaining screw 80 which screws into the forward end of the shaft 64. A fine wire spring 10 81 is coiled around the hub 77 of the pinion within the box-like member 70, one end of said spring being hooked to engage with the slot 73 in the rim of the member 70 and the other end of said spring passing through a 15 drill hole in the hub 77 of the pinion and then being bent back to prevent accidental displacement from said drill hole. Between the coiled spring 81 and the body of the pinion the hub 77 of said pinion is provided with 20 a stop or pin 82 and the coiled spring tends to maintain said pin 82 normally in engagement with the stop 72 on the member 70, this position of the parts being shown in Figs. 4 and 7.

Referring now to the operation of the 25 parts, the connecting or engaging device or pinion 78, as shown in Fig. 1, normally lies just below and out of engagement with the teeth of the carriage rack 15, which rack normally engages with the feed pinion 16. 30 When the tabulating key 49 is adequately depressed it operates through the auxiliary lever 40, link 38 and arm 35 to turn the column stop bar 33 and bring the column stops 32 thereon into the path of the carriage stop 35 30. As the link 38 is moved longitudinally downward during this stop positioning operation, the arm 50 on said link engages with the lever 52, depressing the right hand arm of said lever and raising the left-hand arm 40 thereof. As the left hand arm is swung upwardly it raises the link 57, swinging the carriage retarding device on its pivots 62 and bringing the pinion 78 into mesh with the rack 15. As the upward movement of the 45 pinion 78 continues the rack 15 will be swung upwardly about its pivots 13 and will disengage from the carriage feed pinion 16. As soon as this disengagement occurs, the carriage will be free to be drawn leftward under 50 the influence of the spring drum 26 and will turn the pinion 78 against the tension of the hair spring 81 from the position indicated in Figs. 4 and 7 to that shown in Fig. 8. This turning movement, it will be noted, amounts 55 almost to a complete revolution of the pinion 78 and is equal in fact to a distance of about fifteen letter spaces, or something like an inch and a half. It will be apparent therefore that during the first part of the 60 movement of the carriage after it has been freed from its step-by-step feeding mechanism, said carriage will run freely from the left towards the right to a predetermined extent independently of the retarding device, which 65 during this free or independent run remains

unaffected. As soon, however, as the pin or engaging or connecting device 82 engages the projection or engaging or connecting device 72 of the member 70, movement will be transmitted through the shaft 64 70 to the rotary or movable part or arms 65 of the retarder and the latter will thereupon be coupled with the rotary member 70 and will be actuated so that thereafter the carriage will be retarded and will continue its 75 movement leftward under the influence of the retarder until the carriage stop 30 engages with the proximate column 32. After the carriage has been arrested by the coöperating tabulating stops 30 and 32, the tabulating 80 and retarding devices will be restored to normal position under the influence of their restoring springs as soon as the pinion 78 has been moved downward far enough to cause the disengagement of its teeth 79 from the 85 teeth of the carriage rack 15. Said pinion will be turned in reverse direction under the influence of the spring 81, from the position shown in Fig. 8 back to the normal position shown in Figs. 4 and 7. The pinion 78 is 90 small and very little power is needed to turn it so that the spring 81 may be of exceedingly fine wire, such as a hair spring. This construction in which a fine spring is employed is a simple one and I prefer it, but, 95 if desired, the spring may be dispensed with and the rotary member may be restored to the normal relation with the retarding device by some other means. The operation above outlined may be repeated, of course, 100 as often as desired.

It will be noted that by my invention I provide a lost motion connection between the carriage or traveling element and the retarding device such that when the carriage 105 is released from its step-by-step feeding mechanism it may move freely a sufficient distance to acquire considerable speed before the retarding device begins to operate on said carriage. The initial movement of the 110 carriage free from the influence of the retarder is of such extent, however, that should said carriage be arrested by the engagement of the coöperating tabulating stops before said retarder is taken up, still the impact of 115 the co-acting stops would not be sufficiently great to be harmful. It is only on comparatively long runs that the carriage acquires sufficient momentum to cause a too severe impact of the arresting parts and it is apparent that by my present invention such harmful impact will be avoided because the retarding device will at that time be operative.

The invention is in principle, I believe, broadly new and I desire to claim it broadly 125 and do not wish to be limited to the particular mechanism for carrying it out shown and described herein. Various other means may be employed for obtaining the results obtained by the mechanism illustrated and said 130

mechanism itself may be modified in various ways without departing from the scope of the invention. One example of such modifications is illustrated in Fig. 9 wherein is shown 5 a toothed rotary member or pinion represented by the reference numeral 83 which differs from the pinion 78 first described by providing adjustable means for taking up the 10 retarding device or connecting it with the carriage. In the modified construction the hub or boss 84 of the pinion is provided with a stop pin 85 which is normally maintained in engagement with the stop 72 in the manner hereinbefore explained. To the left of 15 said stop pin 85 the hub may be provided with a plurality of threaded radial openings 86 spaced apart which are adapted to receive a screw stop 87. When the pinion 83 engages with the carriage rack and the carriage 20 is released, said pinion will be turned freely until the screw stop 87 engages with the projecting stop 72 to actuate the retarding device. It will be apparent that the amount of 25 free turning movement of the pinion 83 will depend upon the distance the screw stop 87 is from the normally engaged stop 85 and that this distance may be varied as desired by moving the screw stop from one hole 86 to another. It will furthermore be apparent 30 that if it is desired to increase the free initial movement of the carriage instead of decreasing it, that said increased movement may be provided for by interposing an additional rotary member loosely mounted on the shaft 35 64 between the rotary member or pinion 78 and the member 70 fast on the shaft 64, said member being provided with stop portions and being adapted to be turned by the pinion to effect an operative connection between the 40 latter and the retarding device proper.

What I claim as new and desire to secure by Letters Patent, is:—

1. In a typewriting machine, the combination of a carriage, a carriage retarding device, means to connect the retarding device to the carriage, and means to enable the carriage to travel freely prior to the action of said retarder.

2. In a typewriting machine, the combination of a power driven carriage, a carriage retarding device actuated by the carriage, and means for operatively connecting said retarding device with the carriage after the latter has moved freely and uninterruptedly a predetermined distance and for maintaining said retarding device connected with said carriage during the remainder of the run of the latter.

3. In a typewriting machine, the combination of a power driven carriage, a carriage retarding device, and a lost motion mechanical connection between said retarding device and said carriage.

4. In a typewriting machine, the combination of a power-driven carriage; a carriage

retarding device including a movable part; a key; and means for connecting said carriage with said retarding device, said means including an engaging device, said key being operative to connect said engaging device with 70 said carriage so as to cause movement of said means to a predetermined extent independently of said movable part.

5. In a typewriting machine, the combination of a power-driven carriage; a carriage retarding device including a movable part; a key; and means for connecting said carriage with said retarding device, said means including engaging devices, said key being operated to connect one of said engaging devices with said carriage to move said means independently of said movable part and to connect another of said engaging devices with said movable part.

6. In a typewriting machine, the combination of a power driven carriage, a carriage retarding device including a movable part, and a rotary member operative by the carriage, said member after it has been turned a predetermined extent being coupled with the 90 movable part of said retarding device.

7. In a typewriting machine, the combination of a power driven carriage, a carriage retarding device, a rotary member, means for connecting said rotary member with the 95 carriage, and a lost motion connection between said rotary member and said retarding device.

8. In a typewriting machine, the combination of a power driven carriage, a carriage 100 retarding device comprising a rotary part, a rack connected with said carriage, a toothed rotary member or pinion operative to engage said rack, and lost motion connections between said pinion and the rotary part of said 105 retarding device whereby said pinion is first turned by said rack and thereafter the rotary part of said retarding device is turned by said pinion.

9. In a typewriting machine, the combination of a power driven carriage, a carriage retarding device comprising a rotary part, a rack connected with said carriage, a toothed rotary member or pinion coöperative with 110 said rack, and means normally maintaining said pinion in a position wherein it is inoperative on the rotary part of said retarding device, the pinion after it has been turned a predetermined extent becoming operative to turn the rotary part of the retarding device. 120

10. In a typewriting machine, the combination of a power driven carriage, a rack connected with said carriage, a shaft, a toothed rotary member or pinion loosely mounted on said shaft, a retarding device comprising a 125 part fixed on said shaft, and a spring normally maintaining said pinion in a position wherein it is inoperative on the rotary part of said retarding device.

11. In a typewriting machine, the combi- 130

nation of a power driven carriage, a rack connected with said carriage, a shaft, a toothed rotary member or pinion loosely mounted on said shaft and having a projecting portion, a 5 retarding device comprising a part fixed on said shaft, a spring normally maintaining the projecting portion of said pinion in contact at one point with the part of the retarder on the shaft, said pinion being rotatable to engage the part at another point.

12. In a typewriting machine, the combination of a power driven carriage, carriage escapement mechanism therefor, a rack pivoted on the carriage and normally connected 15 with said escapement mechanism, a retarding device comprising a bearing pivotally mounted on the frame of the machine, a casting fixed to said bearing, a shaft rotatable in said bearing, an arm or blade fixed on said 20 shaft, and a stop portion or lug fixed on said shaft, a spring pressed pinion loosely mounted on said shaft and having a portion normally in contact with the stop portion or lug of the retarding device, said pinion being 25 normally disengaged from said pivoted rack, and hand operated means for moving said retarding device and said pinion to cause said pinion to separate said pivoted rack from said escapement devices and to connect said 30 carriage with said retarding device.

13. In a typewriting machine, the combination of a carriage and a carriage actuated retarding device which includes a movable part that is continuously operative on the 35 carriage to retard said carriage during the greater portions of long runs of said carriage, said movable part being inoperative during short runs of said carriage.

14. In a typewriting machine, the combination of a power driven carriage, a carriage retarding device actuated by the carriage, means for operatively connecting said retarding device with the carriage after the carriage has moved freely a plurality of letter space 45 distances, and means for varying the number of letter space distances through which the carriage may move before the retarding device is connected with it.

15. In a typewriting machine, the combination of a power driven carriage, a carriage retarding device, a rotary member operative by the carriage, said rotary member after it has been turned a predetermined extent being operative to actuate the retarding device, 55 and means for varying the extent which the

rotary member may move before becoming operative to actuate the retarding device.

16. In a typewriting machine, the combination of a carriage, and retarding mechanism therefor including a movable element and 60 a stationary element, said retarding mechanism being provided with means for insuring a preliminary movement of the carriage before the movable element of said retarding mechanism is brought into action.

17. In a typewriting machine, the combination of a power-driven carriage; a carriage retarding device including a movable part; a key; and means for connecting said carriage with said retarding device, said means includ- 70 ing an engaging device, said key being operative to connect said engaging device with said carriage to move said engaging device to a limited extent independently of said movable part.

18. In a typewriting machine, the combination of a carriage, a retarding device, a connecting device, means for bringing said connecting device into engagement with the carriage, and a second connecting device con- 80 nected operatively to the retarding device, said second device being coupled with and moved by the first connecting device after said first connecting device has itself been moved independently by said carriage.

19. The combination of a carriage, a retarding device normally in inoperative condition, means for connecting the retarding device with the carriage while said retarding device is in inoperative condition, and means 90 for rendering the retarding device operative, said last named means being actuated by the carriage travel.

20. The combination of a carriage, a retarding device, means for connecting the 95 retarding device to the carriage, said means being adapted to move with the carriage to a limited extent while the retarding device remains inactive, and means for subsequently connecting the retarding device with the carriage so as to re-act thereon.

Signed at the borough of Manhattan, city of New York, in the county of New York, and State of New York, this 19th day of April A. D. 1906.

MORRIS W. POOL.
